(57) **CLAIM**

We claim the ornamental design for decorative shielding for combine harvester, as shown and described.

DESCRIPTION

FIG. 1 is a top plan view of the decorative shielding for combine harvester in relationship to the unclaimed combine. FIG. 2 is an elevational view of the shielding as seen from the left of the unclaimed combine.

FIG. 3 is an elevational view of the shielding as seen from the right of the unclaimed combine.

FIG. 4 is an elevational view of the shielding as seen from the front of the unclaimed combine; and,

FIG. 5 is an elevational view of the shielding as seen from the rear of the unclaimed combine.

The broken lines showing the unclaimed combine are for illustrative purposes only and form no part of the claimed design.
